[57] CLAIM

The ornamental design for an electronic baseball game
housing, substantially as shown and described.

DESCRIPTION

FIG. 1 is a top perspective view (cover open) of an
electronic baseball game housing embodying my de-
sign;

FIG. 2 is a front view (cover closed) of said electronic
baseball game housing;

FIG. 3 is a right side view (cover closed) of said elec-
tronic baseball game housing;

FIG. 4 is a left side view (cover closed) of said elec-
tronic baseball game housing;

FIG. 5 is a rear view (cover closed) of said electronic
baseball game housing; and

FIG. 6 is a bottom plan view of an electronic baseball
game housing embodying my design.

FIG. 1

FIG. 2

FIG. 3
